UNITED STATES PATENT OFFICE.

JOHN EDWARD OGDEN, OF MOUNTAINVILLE, NEW YORK, AND CHARLES C. TOMKINSON,
OF PLAINFIELD, NEW JERSEY; SAID TOMKINSON ASSIGNOR TO SAID OGDEN.

DOOR.

1,275,591.

Specification of Letters Patent. Patented Aug. 13, 1918.

Application filed September 20, 1916. Serial No. 121,106.

To all whom it may concern:

Be it known that we, JOHN EDWARD OGDEN, a citizen of the United States of America, and a resident of Mountainville, Orange county, and State of New York, and CHARLES C. TOMKINSON, a citizen of the United States, and a resident of Plainfield, Union county, and State of New Jersey, have invented certain new and useful Improvements in Doors, of which the following is a specification, reference being had to the accompanying drawings, forming a part thereof.

Our invention relates to doors for pier sheds, warehouses and the like, and has for one object to provide a door of this character that shall be adapted to swing overhead in opening with a minimum floor clearance.

Another object is to provide means for supporting the weight of the door not only in its open position when it is substantially horizontal, but also in its intermediate positions as it is being opened or closed.

Another object is to provide a hoisting mechanism for doors of the character above indicated, that shall serve not only to open and close the door, but also to support the door independently of stationary brackets or other means in all positions of the door.

In order that our invention may be thoroughly understood, we will now proceed to describe the same in the following specification and then point out the novel features thereof in appended claims.

Referring to the drawings:

Figure 1 is a sectional elevation of a door arranged and constructed in accordance with our invention.

Fig. 2 is a view corresponding to Fig. 1 except that the door is shown in its open position.

Fig. 3 is a sectional plan view, taken on the line 3—3 of Fig. 1, and

Fig. 4 is a view corresponding to Fig. 1, of a slightly modified arrangement which also embodies our invention.

Another modification of our invention is shown in Figs. 5 and 6 which correspond respectively to Figs. 1 and 2.

Fig. 7 shows a slight variation of the structure of Fig. 5, and is also a sectional elevation.

Figs. 8, 9 and 10; Figs. 11, 12 and 13; and Figs. 14, 15 and 16 correspond respec-

tively to Figs. 5, 6 and 7 and each of these groups of figures shows sectional elevations with the door closed and opened, of one structure, and an elevation with the door closed, of a slightly modified structure.

Corresponding parts are designated by the same reference characters in all the figures.

The invention is shown as applied to two-section doors in Figs. 1 to 4 inclusive, and to a single section door in the remaining figures.

Referring first to Figs. 1, 2 and 3, 20 designates the wall of a building in which are hollow reinforced concrete beams 21 and a door opening 22 having a lintel 23 and adapted to be closed by a door having an upper section 24 and a lower section 25. The door is provided with a hoisting mechanism 26 connecting the elevating chains 27 to brackets or arms 28 near the respective lower corners of the bottom door section 25.

The upper door section 24 is provided with guide channels 29 in which the lower section 25 slides when the door is being opened. At the sides of the door opening, stationary guideways 30 are provided to receive the lower section when the door is closed and the sections are only slightly overlapped as shown in Fig. 1. The hoisting chains 27 extend over suitable sheaves 31 in the usual manner to counterweights 32. The hand chain 33 depends from the hoisting mechanism and constitutes a convenient means for actuating the same. The counterweights are preferably disposed in the hollow beams 21 as clearly shown in Fig. 3.

At a considerable distance above the door opening on the wall 20 is a sheave 34 mounted in stationary brackets 35 and there are a pair of sheaves 36—37 secured near the edge of the upper section 24 of the door, one pulley being located near the upper corner of the upper section, and the other at an intermediate point in the length of the door section as clearly shown in Fig. 1.

There is an endless chain or flexible cord 100 extending over the pulleys 36—37 and over the supporting sheave 34.

The operation of opening the door is as follows: The chains 27 are raised by the hoisting mechanism to first raise the lower door section 25 into the guides 29. Its movement relative to the upper door section is limited by some suitable means so

that the continued movement of the hoisting chains will cause the lower edges of both door sections to move upward vertically. The door sections are then free to swing inwardly to the extent permitted by the length of the chain 38, until they have reached their fully opened position.

The arrangement of parts is such that the endless chain or cable is always in tension and serves to support the door as it moves from its closed to its open position, and in its open position.

The counterweights must be of approximately the same weight as that of the lower door section and obviously are insufficient for supporting the entire weight of the two door sections when they are open and in the arrangement of our invention they only support a part of the weight, the remainder being borne by the chain 38 under these conditions.

Attention is particularly directed to the fact that by this arrangement the chain or cord is never slack and always performs its function in assisting the counterweight to support the door. In closing the operation is reversed. When the support of the hoisting chains is removed from the upper door section it will hang on the chain 38 and as the sheave 37 which sustains this weight is offset inwardly from the plane of the door opening it will cause the upper edge of the upper door section to seat against the lintel 23.

It is desirable, particularly for relatively wide doors, to provide a supporting chain 38 and sheaves 34, 36 and 37 at each lateral edge of the door, but the foregoing description will suffice for either a single or a

double arrangement.

Instead of the sheaves 36 and 37 and the chain 38, a chain 41 may extend over the pulley 34 and be attached to the upper door section near one of its edges as shown in Fig. 4, the respective ends of the chain 41 being connected to a point near the top and to an intermediate point in the length of the upper section.

Referring now to Figs. 5 and 6, our invention is applicable to a single section as well as a two-section door, and in fact may be utilized with doors having one or more sections.

A single section door is here designated 44 and is provided with sheaves 45 and 46 which correspond to sheaves 36 and 37, and are secured to its lateral edge.

Instead of the single fixed sheave 34, we provide in this arrangement two sheaves 47 and 48 which are located substantially in the same plane as the pulleys 45 and 46. The sheave 47 is mounted on a bracket 50 which holds it relatively close to the wall 20 and the sheave 48 on a bracket 51 which is spaced above the bracket 50.

In the arrangement of Figs. 1 to 4 inclusive, the flexible chains 38 and 41 have a triangular form while the arrangement of Figs. 5 and 6 produces a quadrilateral figure except when the door is closed. A continuous chain or cable 42 extends over the sheaves 45-46-47-48 and supports the door as it moves from its closed to its open position, and in its open position, as shown in Fig. 6.

By properly positioning the sheaves 47 and 48 and spacing the sheaves 45 and 46, the chain or flexible cable will be of the proper length for both the open and closed positions of the door, and the necessity for a stop is avoided.

The distance between the sheaves 47 and 48 has no shortening effect upon the chain when the door is in its closed position but has a material shortening effect upon the chain when the door is in its open position, which effect may be increased by increasing the distance between these sheaves 47 and 48.

As shown in Fig. 7, the sheaves 47 and 48 may be replaced by brackets 52 and 53 to which the respective ends of the chain 43 are attached. The chain extends over the sheaves 45 and 46 as in the arrangement of the previous figures and the operation of the door is substantially the same in both cases. The arrangement of Figs. 5 and 6 has the advantage that wear on the chain or cable, is more evenly distributed and furthermore, the friction which opposes the opening and closing of the door is reduced.

As in the case of the arrangement shown in Figs. 5 and 6, the shortening effect upon the chain may be varied by changing the position of bracket 52 relative to that of bracket 53.

In Figs. 8 and 9 the one-section door 44 is provided with a pair of sheaves 54-55 which are relatively close together and near the center of the door at its edge. Above the door opening is a sheave 56, and an endless chain or cable 57 extends over the sheaves.

The sheaves and chains are preferably arranged in duplicate on their respective edges of the door in all of the modifications.

As shown in Fig. 10, the sheaves 54-55 may be omitted and a chain 58 substituted for the chain 57, the respective ends of the chain 57 being affixed to the door at points 59-60 corresponding in location to the sheaves 54-55.

In Figs. 11 and 12 another modification of our invention is illustrated, according to which a sheave 61 is mounted outside of the plane of the door, and a sheave 62 considerably above the door opening and substantially in the plane of the door. The sheaves 54-55 are used as in the previous figures. This arrangement has the advantage of more effectively supporting the weight of

the door through the chain 63 which extends around the pulleys. In Fig. 13 the sheaves 61 and 62 are removed and the respective ends of a chain 64 is affixed at 5 points which correspond in location to these sheaves.

In Figs. 14 and 15 a suspension arrangement is provided which corresponds in some respects to that shown in Figs. 1 and 2. It, 10 however, comprises a single section door 44 which is provided with a sheave 65 at an intermediate point in its length, and a sheave 66 near its upper end. A sheave 67 is supported on a bracket 68 at a considerable 15 distance above the door opening but not sufficiently high to maintain a fixed length of chain for all positions of the door. The operation however, is made substantially the same as the arrangement of Figs. 20 1 and 2, by the use of a pair of stops 69 and 70 which are both located between the sheave 67 and the sheave 66. These stops limit the freedom of movement of the chain and allow one section of the chain to be 25 under tension while the other section between the stops may be slack.

In the arrangement illustrated, there is considerable slack in the section of the chain between stops when the door is closed 30 and this slack is taken up when the door is open.

Instead of the sheaves 65 and 66 the ends of the chain may be affixed to the door at corresponding points 71 and 72 as shown in 35 Fig. 16, in which case a single stop 69^a is required if a part of the chain is to be slack during a part of the operation.

We have not shown a hoisting mechanism in any of the modifications except that of 40 Figs. 1, 2, and 3, because mechanisms of this character are well known.

Various modifications may be made within the spirit and scope of our invention and we intend that only such limitations be imposed as are indicated in the appended 45 claims.

What we claim is:

1. The combination with a frame having a door opening, of a door having a vertically guided pivotal axis, hoisting mechanism connected to the door near its pivotal axis operating to exert a pull in the vertical plane of movement of said axis, a freely rotatable sheave affixed above the door opening, and a flexible supporting member independently of the hoisting mechanism extending over the sheave and connected with the door at more than one point above said pivotal axis.

2. The combination with a frame having a door opening, of a door having a vertically guided pivotal axis, hoisting mechanism connected to the door near its pivotal axis, operating to exert a pull in the vertical plane of movement of said axis, a freely

rotatable sheave affixed above the door opening, a pair of spaced sheaves mounted upon the door, and a flexible supporting member independent of the hoisting mechanism extending over the fixed sheave on the frame 70 and the spaced sheaves on the door.

3. The combination with a frame having a door opening, of a door having a vertically guided pivotal axis, means for vertically guiding the door near its lower end, 75 a hoisting mechanism connected to the door near the bottom operating to exert a pull in the vertical plane of movement of said axis, a freely rotatable sheave affixed above the door opening, and a flexible supporting member independent of the hoisting mechanism extending over the sheave and connected to spaced points above the bottom of the door one of which is near the upper end of the door.

4. The combination with a frame having a door opening, of a door having a vertically guided pivotal axis, means for vertically guiding the door near its lower end, a hoisting mechanism connected to the door near the bottom operating to exert a pull in the vertical plane of movement of said axis, a freely rotatable sheave affixed above the door opening, a sheave mounted on the door near the top, a second sheave mounted on 95 the door at an intermediate point, and a flexible member extending over the aforesaid sheaves and arranged to support the upper end of the door in its intermediate and open positions.

5. The combination with a frame having a door opening, of a door having an upper and a lower section, guideways on the upper section for the lower section, means for vertically guiding the lower end of the bottom section, hoisting means connected to the lower end of the bottom section operating to exert a vertical pull thereon, a freely rotatable sheave affixed above the door opening, and a flexible member extending over the sheave and connected with the upper door section at two vertically spaced points materially above the lower end thereof and arranged to support the upper end of the door in its intermediate and open positions.

6. The combination with a frame having a door opening, of a door having an upper and a lower section, guideways on the upper section for the lower section, means for vertically guiding the lower end of the bottom section, hoisting means connected to the lower end of the bottom section operating to exert a vertical pull thereon, a freely rotatable sheave affixed above the door opening, and a flexible member extending over the sheave and connected to vertically spaced points on the upper door section above the lower end thereof, one of which is near the upper end of said upper door section.

7. The combination with a frame having a

- door opening, of a door having an upper and a lower section, guideways on the upper section for the lower section, means for vertically guiding the lower end of the bottom section, hoisting means connected to the lower end of the bottom section operating to exert a vertical pull thereon, a freely rotatable sheave affixed above the door opening, and a flexible member extending over the aforesaid sheave and connected with the upper door section at two vertically spaced points materially above the lower end thereof and arranged to support the upper end of the door in its intermediate and open positions.
8. The combination with a frame having a door opening, of a door having a vertically guided pivotal axis, hoisting mechanism connected to the door near its pivotal axis operating to exert a pull in the vertical plane of movement of said axis, and a flexible supporting member independent of the hoisting mechanism connected to one or more fixed points above the door opening and to a plurality of vertically spaced points on said upper door section materially above the lower end thereof, so arranged that the flexible member is adapted to support the upper end of the door in its intermediate and open positions.
9. The combination with a frame having a door opening, of a door having a vertically guided pivotal axis, a freely rotatable sheave affixed above the door opening, a flexible member extending over the sheave and with its ends connected to the door at vertically spaced points thereon, and a stop affixed to said flexible member and a fixed abutment for said stop.
10. The combination with a frame having a door opening, of a door having a vertically guided pivotal axis, a bracket affixed above the door opening, a sheave rotatable therein, a flexible member extending over the sheave and with its ends connected to the door at vertically spaced points thereon, said flexible member being of greater length than the combined distances from said points of attachment to the sheave, and a stop affixed to said flexible member and arranged to engage said sheave bracket when the door is in closed position.
11. The combination with a frame having a door opening, of a door having a verti-

cally guided pivotal axis, a freely rotatable sheave affixed above the door opening, a pair of spaced sheaves mounted on the door, a flexible member extending over the fixed sheaves on the frame and the spaced sheaves on the door, and a pair of spaced stops on the flexible member between the fixed sheave and one of the door sheaves.

12. The combination with a frame having a door opening, of a door having a vertically guided pivotal axis, a freely rotatable sheave affixed above the door opening, a pair of spaced sheaves mounted on the door, a flexible member extending over the fixed sheaves on the frame and the spaced sheaves on the door, and a pair of spaced stops on the flexible member between the fixed sheave and one of the door sheaves, the fixed sheave being so arranged that the entire flexible member is in tension when the door is open and so that a portion of the member is in tension when the door is closed.

13. The combination with a frame having a door opening, of a door adapted to swing away from the door opening at the top, hoisting means connected with the bottom of the door, a plurality of spaced members above the door operating to exert a vertical pull thereon opening in substantial alignment vertically, and a flexible member extending over said members and connected to the door at spaced points above the bottom of the door.

14. The combination with a frame having a door opening, of a door adapted to swing away from the door opening at the top, a plurality of freely rotatable spaced pulleys above the door opening in substantial alignment vertically, a flexible member extending over the pulleys and connected to the door at spaced points above the bottom of the door, and a hoisting mechanism independently connected to the door near the bottom operating to exert a vertical pull thereon.

In witness whereof, we have hereunto set our hands this 18th day of September, 1916. 100

JOHN EDWARD OGDEN.
CHARLES C. TOMKINSON.
